UNITED STATES PATENT OFFICE

EMIL CZAPEK AND RICHARD WEINGAND, OF BOMLITZ, NEAR WALSRODE, GERMANY

CELLULOSE PRECIPITATING AGENT

No Drawing. Application filed August 31, 1926, Serial No. 132,900, and in Germany September 1, 1925.

This invention has reference to improvements in the precipitation of cellulose from its solutions by means of which a very strong and superior grade of an artificial fibrous material may be produced. In the manufacture of artificial silk from viscose, as heretofore practiced aqueous or acidified aqueous salt solutions have been employed as a rule. In accordance with our experiments it has been ascertained that a precipitating bath in which the water is replaced by methanol presents great advantages over the precipitating baths heretofore known. Thus it has been found for example that a precipitating bath consisting of a solution of magnesium chloride or magnesium-sulphate in methanol and an inorganic acid is particularly suitable. It is also possible within the scope of this invention to employ a mixture of methanol and an inorganic acid or merely a solution of an inorganic salt in methanol.

These precipitating baths among other important advantages are particularly distinguished from the baths heretofore known by the fact that they produce a very rapid precipitation. Moreover, the threads produced in this manner immediately after their production possess a very great tearing resistance owing to the dehydrating action of these baths, and are not liable to stick together, as it frequently occurs in the case of precipitating baths comprising aqueous solutions; and the finished threads are also distinguished by being comparatively highly water-proof. It is also possible to manufacture threads of a high degree of fineness with these precipitating baths owing to the great tearing strength in the wet condition, and the threads may be easily washed without injury. In a modification the precipitation may be proceeded by a coagulation with substantially pure methanol.

We are aware that it has been suggested in United States Patent No. 792,888 to employ a mixture of methyl-alcohol with acetic

acid and sodium-acetate as a precipitating bath for artificial silk; but this bath is of no practical importance on account of its very slow precipitating velocity, and in view of the high prices of acetic acid and of sodium acetate.

It should, of course, be understood that the broad principle of the invention may be carried out and modified to suit existing conditions and without thereby deviating from the spirit and scope of the invention, as set forth in the appended claims.

We claim:

1. In the manufacture of artificial silk from viscose and similar cellulose solutions, the introduction of the cellulose solution in the form of threads into a precipitating bath containing, in non-aqueous solution in methanol, an inorganic precipitant soluble in methanol.

2. In the manufacture of artificial silk from viscose and similar cellulose solutions, the introduction of the cellulose solution in the form of threads into a precipitating bath containing, in non-aqueous solution with methanol, an inorganic salt soluble in methanol.

3. In the manufacture of artificial silk from viscose and similar cellulose solutions by introducing the cellulose solutions in the form of threads into a precipitating bath, this bath containing, in non-aqueous solution with methanol an inorganic acid soluble in methanol.

4. In the manufacture of artificial silk from viscose and similar cellulose solutions, the introduction of the cellulose solution in the form of threads into a precipitating bath containing, in non-aqueous acidulated solution with methanol, an inorganic salt soluble in methanol.

5. In the manufacture of artificial silk from viscose and similar cellulose solutions the introduction of the cellulose solution in the form of threads first into a bath of pure

methanol and then into a bath containing, in non-aqueous solution with methanol, an inorganic precipitant soluble in methanol.

6. As a new article of manufacture artificial silk of very high tearing strength and
5. waterproof qualities consisting of regenerated cellulose solidified by an inorganic precipitant with a non-aqueous solution of methanol.

10 In testimony whereof we affix our signatures.

DR. EMIL CZAPEK.
DIPLO. ING. RICHARD WEINGAND.
